DIMPLING TOOL

James G. Hurst, Los Angeles, Calif., assignor to
 Douglas Aircraft Company, Inc., Santa Monica,
 Calif.

Application September 7, 1942, Serial No. 457,633

11 Claims. (Cl. 153—21)

This invention relates to the art of dimpling rivet holes in relatively thin and resilient metal sheets preparatory to driving flush rivets or of otherwise forming such sheets adjacent apertures therein between a driving die and a bucking die or anvil. Specifically, the invention is contained in a dimpling tool adapted for use in closely restricted areas where it is difficult or impossible to employ two men, one "driving" the dimple and one "bucking" the impulses of the tool.

In certain industries, such as the airplane industry, metal sheets are secured together by flush riveted joints so that a smooth exterior surface may be obtained. It is found that the most satisfactory joint of this type is obtained by forming a frusto-conical shaped recess surrounding each rivet hole in the sheets to be joined so that the head of a rivet of the countersunk type will seat therein. This operation will be hereinafter referred to as "dimpling" and is not to be confused with the usual type of countersinking which is formed by cutting away sufficient metal of one or more sheets to receive all or part of a rivet head. The method of fluid control for rivet guns and other impact tools is old in the art and therefore it is understood that this invention deals primarily with improvements in the gun mechanism.

It is the principal object of this invention to provide a simple efficient means for forming dimples in relatively thin and resilient metal sheets preparatory to driving flush rivets.

Another object is to provide a dimpling tool which will save both time and energy in its ability to form dimples in restricted areas where it is difficult to employ two men.

Another object is to provide a dimpling and bucking tool in one unit.

Another object is to provide a simple means for applying a clamping action between the main body of a dimpling tool and an anvil member forming a part thereof so that the sheet or sheets to be dimpled will be held solidly therebetween.

Another object is to provide a solidly held anvil member to buck the blows of a hammer member of the gun.

Another object is to provide an anvil member which may be easily fastened to a part of the gun by the operator from the reverse side of the sheet or sheets to be dimpled.

Another object is to provide a dimpling gun having a hammer and anvil in the form of a male and female die which co-operate to form a perfect dimple.

Still another object of this invention is to pro-

vide an automatic centering device for the co-acting dies.

Further objects and advantages of the invention will be brought out in the following description taken in connection with the accompanying drawings and appended claims.

Referring now to the drawings:

Figure 1 is a longitudinal view in section of a dimpling gun embodying the invention, showing the position which the parts assume when the striker piston is at the end of its rearward stroke.

Figure 2 is a longitudinal view in section of the dimpling gun of Figure 1 showing the striker piston thereof in the striking position.

Figure 3 is an enlarged longitudinal fragmentary view in section of the dimpling gun of Figure 2 showing the first step in the dimpling of a sheet.

Figure 4 is an enlarged longitudinal fragmentary view in section similar to Figure 3 but showing the second or driving step in the forming of the dimple.

Figure 5 is an enlarged longitudinal fragmentary view in section similar to Figure 4 but showing the finished dimple, and

Figure 6 is an enlarged plan view of the completely dimpled hole.

Percussive tools and the control thereof are well known in the art. For example, Patent Number 2,101,159 shows a pneumatic gun and its controlling mechanism in detail. The present invention is an improvement on such a tool and accordingly the description and drawings herein do not repeat the details of these known devices.

As best shown in Figures 1 and 2 of the drawings, the dimpling gun consists essentially of a cylinder or barrel 10 to which is assembled a pistol type grip handle 11. The grip handle is adapted at 11' to be connected to a fluid pressure supply line and is provided with an inlet duct 12 leading from the point of connection to the interior of the cylinder 10. A valve 13 has a stem 15 which is slidable in a bore 16 in the grip handle and has a head 17 mounted thereon and engageable with a seat 18 to thereby control the passage of fluid in the duct 12. A spring 21 is interposed between the valve head 17 and a threaded plug 22 to hold the valve yieldably against its seat 18. From the valve, a continuation of the duct 12 leads directly to the cylinder and delivers live motive fluid to the cylinder during one phase of the gun's operation and serves as an exhaust during another phase.

The forward end of the valve stem 15 protrudes

from the grip handle and bears against a trigger 23 pivotally carried by a pin 24 set in a slotted ear 25 formed on the handle 11.

To form the rear closure for the cylinder 10 a hub-like extension 26 on a knurled hand wheel 27 is held rotatably in a central bore of a screw type plug 28, the plug 28 having threaded engagement with the left end of the cylinder 10. An annular groove 26a in the hub 26 receives a set screw 29 set in the plug 28 so that the hand wheel may thereby be restrained from axial movement with respect to the plug 28 and cylinder 10. A central bore through the hand wheel hub 26 allows a tension rod 30 to be passed therethrough. A conically shaped head 32 on the left end of rod 30 fits within a countersunk hole 31 in the wheel 27, preventing rightward axial movement of the rod in the cylinder 10. A key 33 in keyway slots in the head 32 and wheel 27 prevents relative rotation of the rod 30 and wheel 27. The hole 31 is closed by a threaded plug 34 which prevents leftward axial movement of the rod in the cylinder 10. When the tension rod is assembled to the dimpling gun a threaded portion 30a and a rounded portion 30b extend forwardly therefrom.

A piston chamber 35 is provided in the cylinder 10 and a striker piston 36 reciprocates therein. A central bore in the striker piston enables the tension rod 30 to be passed therethrough. The striker piston is adapted to strike a head 37 on a hammer member or die 38 which is also provided with a central bore 39. The forward portion of the hammer member 38 is formed in the shape of a conical frustum having an included angle of substantially 100°. The hammer member closes the front portion of the cylinder and is maintained in a slidable relation thereto by reason of its being supported in a central bore 40 of a cylinder 41. The cylinder 41 and cylinder 10 constitute a housing for the hammer 38 and associated parts.

An annular stop shoulder 42 is provided in the forward portion of the cylinder piston chamber 35 against which rests a shock ring 43 so as to limit the forward travel of the hammer head. A spring 44 is wrapped around the hammer member 38 and is interposed between the forward face of the hammer head 37 and the forward portion of a counterbore 45 in the cylinder 41. An outwardly projecting annular flange 46 on the cylinder 41 allows the cylinder 41 to be held securely to the end of the cylinder 10 by a retaining cap 47 which is threaded thereon. A gasket 48 is inserted between the cap 47 and flange 46 to form an airtight joint. Thus when fluid is directed against the hammer member to return it to its original position there will be no leakage past this joint to prevent this return movement.

The central bore through the striker piston 36 and the hammer member 38 enables the tension rod which extends therethrough to be rotated freely so that after the threaded end of the rod has been passed through the sheet to be dimpled an anvil member or bucking die 49 may be rapidly threaded thereon. The anvil member is provided with a recess 51 upon its slightly beveled bearing or operative face 52 which recess has an included angle of substantially 100° corresponding to the nose of the hammer member 38.

The 100° angle mentioned hereinabove corresponds to a standard 100° rivet commonly used. However, it is to be understood the angle may be varied in accordance with the type of rivet it is desired to use.

In operating the gun the self-centering rod 30 is inserted into a hole 53 drilled in the sheet to

be dimpled corresponding to the diameter of the rivet used. This self-centering movement is accomplished by the rounded portion 30b on the tension rod extremity which cooperates with the recessed portion 51 of the anvil member 49. The threads on the tension rod are adapted to cooperate with those provided in the anvil member so that the latter may be threaded thereon from the opposite side of the sheet 56. It will be noted from the drawings (Figures 3, 4 and 5) that a smooth portion of the threaded tension rod engages a similar smooth portion of the anvil member at 58. Thus the anvil member is solidly supported at this point thereby reducing some of the strain which might otherwise be concentrated upon the threads 30a. The knurled adjustment wheel 27 on the rear extremity of the gun is turned, rotating the tension rod, the threaded end of which is threaded into the anvil member 49, so that the sheet of metal is securely clamped between the bearing surface 52 of the anvil member and the bearing or work engaging surface 54 of the cylinder 41. The trigger 23 is depressed, thereby unseating the valve head 17 from the valve seat 18.

25 The released charge of fluid causes the striker piston 36 to deliver a heavy blow to the head 37 of the hammer member 38. The frustum shaped nose of the hammer member is driven against the sheet and forces it to assume the configuration of the recess 51 in the anvil member as shown in Figures 2 and 5 of the drawings. After a blow has been delivered to the hammer member 38 the striker piston 36 is returned to its original position upon release of the trigger 23 by the application of fluid pressure to the forward side of the striker piston through a fluid passage 60 in the manner described in the abovementioned Patent Number 2,101,159.

30 The knurled hand wheel 27 is provided on the rear portion of the pneumatic dimpling gun so that the operator may adjust the pressure of the tool and anvil member against the sheet to be dimpled. With this hand wheel a quick adjustment is provided which enables the operator to 35 spin the centering rod into the anvil member so that a few turns of the hand wheel will draw the anvil member tightly against the sheet to be dimpled.

35 It will also be noted from the drawings, Figures 3, 4 and 5, that the face 52 of the anvil member is provided with a slightly beveled surface. This beveled surface terminates at the periphery of the recessed portion 51. In this manner the flat surface is adapted to provide a 40 perfect matching of the pressure areas on both the outer end face of the cylinder 41 and the anvil member 49 so that there is no possibility of disfiguration of the sheet being dimpled by sharp edges on the anvil member. Thus, each blow of the hammer is guided and delivered directly to the center of the recess 51. In addition each blow of the hammer member is backed by a 45 solidly supported surface, thus precluding any possibility of displacement of the anvil member with resulting irregularity in the dimples so formed.

45 I claim:

50 1. In a tool for die forming work articles comprising apertured plates, the combination of: a tool housing having at one end a work engaging face; a centrally bored die slidably projectible from the housing; a bucking die independent of the work article for cooperating with said projectible die, a tension rod dimensioned to pass 55 through an aperture in the plates, said tension

rod being disposed in the bore of said projectible die and securable to said bucking die, and having an end thrust engagement with said housing preventing movement of said rod toward said work engaging face; and means associated with said rod for placing it under tension to draw said bucking die, when secured to said rod, toward said housing to clamp the work article between said work engaging face and bucking die; and means for applying a force to project the die outwardly relative to the housing into forming contact with the work article while the work article is thus clamped.

2. In a tool for forming work articles comprising apertured plates, the combination of: a tool housing having at one end a work engaging face, and a forming tool projectible from the housing; an anvil independent of the work article for cooperating with said tool, said anvil having at least one threaded bore; and a tension rod having an end thrust engagement with said housing preventing movement toward said work engaging face, said tension rod being dimensioned to pass through one of the plate apertures and being threaded for engagement with said threaded bore whereby the anvil and rod may be relatively rotated to clamp the work article between said work engaging face and said anvil; and means for applying a force to project the tool from the housing into forming contact with the work article while the work is clamped.

3. The combination defined in claim 2, in which said rod is rotatably mounted in said housing, and in addition thereto; means on said housing for rotating said rod.

4. In a tool for die forming work articles comprising apertured plates, the combination of: a barrel having at one end an annular work engaging face and a centrally bored die projectible from said barrel centrally of said face; a bucking die independent of the work article for cooperating with said projectible die, said bucking die having a threaded bore; a tension rod dimensioned to pass through an aperture in the plate, said tension rod being disposed in and projecting at each end from the bore of said projectible die, having an end thrust engagement with said barrel preventing movement toward said work engaging face and threaded at the outer end for engagement with said threaded bore whereby the bucking die and rod may be relatively rotated to clamp the work article between said work engaging face and said bucking die; and means for applying a force to project the projectible die from the barrel into forming contact with the work article while the work is thus clamped.

5. The combination defined in claim 4 in which said means for applying a force to said projectible die comprises a piston hammer reciprocatively movable within said barrel and pneumatic means for effecting said reciprocative movements.

6. The combination defined in claim 4 in which said means for applying a force to said projectible die comprises a piston hammer reciprocatively movable within said barrel and pneumatic means for effecting said reciprocative movements, and in which said projectible die has a hammer head at its inner end and in addition thereto, a coiled compression spring seated between said hammer head and the outer end portion of said barrel 10 for retraction of said projectible die after each outward movement of said hammer.

7. The combination defined in claim 2 and in addition thereto; means for preventing movement of said rod toward the other end of said housing.

15 8. The combination defined in claim 4 in which said work engaging face is normal to the axis of the tool and the operative face of said bucking die outside of the forming surface flares conically at a slight angle away from a plane normal to the axis of the tool.

9. In a tool for die forming work articles comprising apertured plates, the combination of: a barrel having at one end an annular work engaging face; a centrally bored die projectible 25 from said barrel centrally of said face; a bucking die independent of the work article for cooperating with said projectible die, said bucking die having a threaded bore; a tension rod dimensioned to pass through an aperture in the plates, 30 said tension rod being disposed in and projecting at each end from the bore of said projectible die, and threaded at its outer end for engagement with said threaded bore whereby the bucking die and rod may be relatively rotated to clamp the 35 work article between said work engaging face and said bucking die; means for applying a force to project the projectible die from the barrel into forming contact with the work article while the work is thus clamped; and a head secured to the 40 inner end of said rod for end thrust engagement with the inner end of the barrel.

10. The combination defined in claim 9 in which said means for applying a force to said projectible die comprises a hammer head on the inner end of said die, a centrally bored piston hammer slidably centered on said rod and reciprocatively movable within said barrel and pneumatic means for effecting said reciprocative movements.

50 11. The combination defined in claim 4 in which said work engaging face is formed on a separable part of said barrel consisting of a hollow cylinder disposed in fluid tight relation with and concentrically between said projectible die 55 and the body of said barrel and having a radially outwardly extending annular flange between its ends; and in addition thereto a nut threadedly engaging the rim surface of said barrel and formed with a flange for engaging said annular 60 flange to secure said cylinder to the body of said housing.

JAMES G. HURST.
